Attorney:

UNITED STATES PATENT OFFICE

CARL WEBER, OF JACKSONVILLE, FLORIDA, ASSIGNOR TO SHORE-LINE BUILDERS, INC.,
OF JACKSONVILLE, FLORIDA, A COMPANY OF FLORIDA

BULKHEAD-WALL CONSTRUCTION

Application filed March 13, 1928. Serial No. 261,263.

My invention relates to the construction of bulkheads or retaining walls, such as are used for the protection of shorelines and banks of oceans, lakes and rivers, for the retention 5 of earth embankments and fills, for the walls of reservoirs, tanks, swimming pools and the like, and for the core walls in earthen dams and analogous structures.

The object of my invention is to build such 10 retaining walls in strict accordance with sound engineering methods and in an improved manner, so that permanent safe and secure walls of this kind can be built at a lower cost than heretofore.

15 I accomplish this purpose by fabricating interlocking concrete slabs or wall sections with recessed ends, which are supported upon foundation piles, which may be old steel rails. These piles are permanently encased in concrete, 20 poured around them in said recessed ends, so that they form an integral part of the completed structure and take up the vertical loads as well as horizontal thrusts caused by the pressure of the bank or of the 25 water.

The slabs are formed with pilaster extensions on their ends, which meet around a pile and enclose the same. The faces of said ends are grooved or irregularly shaped to interlock 30 with each other, the joint between them being filled with the concrete which is poured around the pile in the recessed ends. The pilasters, formed by the meeting ends of two slabs, may project from the front of the wall, 35 as when it is used for shore protection, or from the back of the wall, as when it is used for boat landings, swimming pools, and the like.

For the foundation piles I use, wherever 40 possible, old railroad rails, which are cheap and offer ideal stiffness, so that they can easily be driven into any kind of earth strata. They also present the advantage that they are easily shortened or lengthened by splicing, 45 without affecting the strength of the wall. Each pile is driven to a given resistance and then their tops are cut off to a uniform level. Other forms of piles can be used, however, when necessary or desirable.

50 The concrete slabs, which are premolded,

may contain any of the known forms of reinforcement and, as stated above, are reversible to bring the pilasters of the wall either on the front side or the back. A concrete coping is usually applied to the top of the 55 wall, and may, if desired, be formed as part of the slabs. The wall may be braced by anchor bolts or batter piles to assist in taking up lateral stresses.

To secure correct horizontal alinement of 60 the slabs and to facilitate the erection of the wall, each slab is provided with hanger rods secured in its ends and supported from the tops of the piles, which may be provided with metal caps over which said rods pass and 65 which also serve to hold the anchor bolts, when these are used. Where the wall is of considerable height, I place one row of slabs above another, the lower row then being supported by the hangers and the upper row 70 being sustained by the lower row.

An embodiment of the invention is illustrated in the accompanying two sheets of drawings, in which,

Fig. 1 is a horizontal section through the 75 wall, showing the pilasters on the front side;

Fig. 2 is a similar view with the pilasters on the rear side;

Fig. 3 is a vertical cross section of the wall 80 through the middle of a slab showing an anchor bolt bracing;

Fig. 4 is a similar view showing batter pile 85 bracing;

Fig. 5 is a cross section of a deeper wall comprising two superposed rows of slabs;

Fig. 6 is a face view of the wall of Fig. 5;

Fig. 7 is a vertical section through a pilaster showing the hanger rods and an anchor bolt connection, and

Fig. 8 is a similar view at right angles to 90 Fig. 7.

A bank to be protected by the wall is indicated at 1 in Figs. 1 to 4, the same having a straight face 2 in Fig. 1 and having recesses 3 for the pilasters, in Fig. 2, the pilasters in the first case being on the front of the wall, whereas in the second case, they are on the rear of the same.

Each slab 5 is formed with a half pilaster 95 extension 4 on one side of each of its ends,

and said extensions are recessed at 6 to enclose the piles 7. Concrete 8 is poured around the piles in said recesses and also fills the joint 10 between the meeting ends 9 of the slabs, which ends are irregularly shaped to interlock with each other.

The piles 7 are first driven, as explained above, at the proper distances apart and to a uniform resistance, and their tops are then 10 cut off to bring them all in the same horizontal plane. If too short, they can be spliced, as stated. Then the slabs, which are preferably provided with the hangers 18, to be more fully described further on, are set in position with 15 their enlarged recessed ends enclosing the piles. Concrete is then poured around the piles, filling said recesses and the joints between the meeting faces of the slab ends. A coping 11 is then placed on top or, if desired, 20 each slab may have a coping section molded integrally with it. If necessary, back anchors 12 are secured to the tops of the piles, or a back brace consisting of a concrete head 13 and a batter pile 14, having its end 15 resting 25 on the top of the pile, may be used.

Where the wall is deep, I use two rows of slabs, tied together at their meeting edges by a concrete lock 17, and in this case, the lower 30 row is supported by the hangers 18 while the top row is supported on the lower row. These hanger rods 18 have their free ends bent and embedded in the end faces of the slabs, as shown in Fig. 8. To support these rods on the piles, I may use metal caps 19, having 35 legs 20 depending on each side of the web of the pile, having a semi-circular top over which the middle of said rods lies, and having a groove in its top to receive the anchor bolt 12.

The slabs and coping may contain any desired form of reinforcement.

From the above description and the illustration, it will be seen that I have provided a construction of retaining wall which is relatively inexpensive, simple to build, yet extremely sturdy and durable.

Having thus described my invention, what I claim is:—

1. A retaining wall, comprising a row of driven metal piles, concrete slabs recessed at 50 their ends to enclose said piles, and hangers passed over the tops of the latter and having their ends embedded in the end faces of said slabs to support and aline the same said recesses being filled with cement to form an integral waterproof structure.

2. A retaining wall, comprising a row of driven metal piles, concrete slabs recessed at 55 their ends to enclose said piles, hangers passed over the tops of the latter and having their ends embedded in the end faces of said slabs to support and aline the same, and shoes fitted on the tops of the piles to support said hangers said recesses being filled with cement to form an integral waterproof structure.

3. A retaining wall, comprising a row of

driven metal piles, concrete slabs recessed at 70 their ends to enclose said piles, hangers passed over the tops of the latter and having their ends embedded in the end faces of said slabs to support and aline the same, shoes fitted on the tops of the piles to support said hangers, and anchor braces for the piles secured in said 75 recesses being filled with cement to form an integral waterproof structure.

4. A retaining wall composed of molded 75 concrete slabs and spaced piles, each slab having a half pilaster extension on one side of each of its ends, an irregularly formed face on its ends and a recess in each of said faces, so that, in assembling the wall, each pair of 80 adjacent slab ends interlock and enclose a pile, and said ends together form a pilaster which may project from the front of the wall or from the rear thereof, said recesses and the joint between said faces being filled with cement to form an integral waterproof structure. 85

5. A retaining wall, consisting of a row of spaced metal piles, and interlocking concrete 90 slabs supported by said piles and filling the spaces between the same, each slab having its ends thickened on one side and recessed to loosely enclose the adjacent piles, said recesses being filled with cement to form an integral waterproof structure. 95

6. A retaining wall, consisting of a row of spaced metal piles driven to a uniform resistance and with their tops in the same horizontal plane, and molded concrete slabs filling the spaces between said piles, said slabs having thickened ends provided with recesses to receive the adjacent piles, the meeting faces of said ends being ribbed and grooved to form an interlocking joint, said recesses and joints being filled with cement to form an integral waterproof structure. 100

In testimony whereof I have hereunto set my hand.

CARL WEBER.
